(57) **CLAIM**

The ornamental design for an electronic device, as shown and described.

DESCRIPTION

FIG. 1 is a rear perspective view of an electronic device according to the invention.

FIG. 2 is a front view of the electronic device of FIG. 1.

FIG. 3 is a rear view of the electronic device of FIG. 1.

FIG. 4 is a left side view of the electronic device of FIG. 1.

FIG. 5 is a right side view of the electronic device of FIG. 1.

FIG. 6 is a top plan view of the electronic device of FIG. 1; and,

FIG. 7 is a bottom plan view of the electronic device of FIG. 1.

The electronic device is not limited to the scale shown herein. As indicated in the title, the article of manufacture to which the ornamental design has been applied is an electronic device, media player (e.g., music, video and/or game player), media storage device, a personal digital assistant, a communication device (e.g., cellular phone), a novelty item or toy.

1 Claim, 5 Drawing Sheets
